(57) **CLAIM**

The ornamental design for combined central component and structural assembly, as shown and described.

DESCRIPTION

FIG. 1 is a perspective view of one side and two ends of combined central component and structural assembly showing my new design;

FIG. 2 is a perspective view of the central component shown in FIG. 1, all sides of the central component being identical;

FIG. 3 is a perspective view of an opposite end and one side of a beam component; and,

FIG. 4 is a side elevational view thereof, the opposite side being a mirror image thereof.
